UNITED STATES PATENT OFFICE.

LEO G. McMULLEN, OF BALTIMORE, MARYLAND.

REAMING MACHINE.

Application filed July 26, 1922. Serial No. 577,656.

To all whom it may concern:

Be it known that I, LEO G. McMULLEN, a citizen of the United States, residing at Baltimore, in the State of Maryland, have 5 invented a new and useful Reaming Machine, of which the following is a specification.

This invention aims to provide a simple means whereby a reaming operation may 10 be carried out under conditions in which the use of a reaming machine of ordinary type would be impossible.

It is within the province of the disclosure to improve generally and to enhance the 15 utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the 20 invention shown can be made without departing from the spirit of the invention.

In the accompanying drawings:—

Figure 1 shows in plan, a device constructed in accordance with the invention, the upper member of the arm being removed; Figure 2 is a longitudinal section; Figure 3 is a cross section taken through the arm; Figure 4 is a fragmental top plan showing a modification; Figure 5 is a section of the structure shown in Figure 4.

The numeral 1 marks the frame of a reaming machine, carrying a reduced projecting arm, denoted generally by the numeral 2, the arm embodying a lower member 3 and an upper member 4, the upper member being held on the lower member by securing elements 5. The members 3 and 4 of the arm 2 are supplied with cooperating recesses 6 defining a chamber, the upper and lower members of the arm being supplied with reduced openings 7 communicating with the chamber, bearings 8 being located in the openings 7 and having flanges 9 engaging the members 3 and 4 of the arm 2 in the chamber formed by the recesses 6.

The ends of shafts 10 are journaled in certain of the bearings 8. A shaft 11 is journaled in the outermost bearing and has a tool holding means which may be in the

form of a socket 12 of any desired shape. Intermeshing pinions 14 are located in the chamber defined by the recesses 6 and are carried by the shafts 10 and 11. The innermost pinion 14 meshes with a gear wheel 15 on a shaft 16, the shaft 16 being power-driven and being located in the frame 1, the lower end of the shaft 16 being journaled in a bearing 17 mounted in an opening in the lower member 3 of the arm 2, the bearing having a laterally projecting flange 19 engaging the lower member 2 of the arm 2.

In practical operation, when the shaft 16 is rotated, motion is transmitted by the gear wheel 15 and the pinions 14 to the tool holding shaft 11, the reamer or other tool being rotated. It is obvious that since the machine includes the reduced arm 12, the reaming operation can be carried out 75 under conditions which would be impossible in the absence of the arm.

A useful but not mandatory adjunct is delineated in Figure 5 of the drawings. If desired, the upper member 4^a of the arm 2^a may be provided with seats 20, parts hereinbefore described being designated, in Figures 4 and 5 by numerals previously used, with the suffix "a". The seats 20 are adapted to receive the reduced fingers 21 on the lower end of a removable bridge 22 carrying an adjustable pressure member, such as a screw 23, threaded into the bridge, the screw comprising a center point 24 and a turning head 25. Obviously, through the 80 instrumentality of the screw 23, the work may be held in place or, considered from a different viewpoint, the arm 2 may be held 85 to the work.

What is claimed is:

1. In a device of the class described, a frame having a reduced projecting arm embodying a lower member, an upper member and securing elements connecting said members, the members of the arm being supplied with cooperating recesses defining a chamber, said members of the arm being equipped with reduced openings communicating with the chamber, bearings located in the openings and engaging said members of the arm within the chamber, shafts journaled in the bearings, the outermost shaft being provided with tool-holding means, and intermeshing pinions located in the chamber and carried by the shafts.

2. In a device of the class described, a frame provided with a reduced arm, a driving shaft at the inner end of the arm, a driven shaft at the outer end of the arm and equipped with tool-holding means, mechanism for connecting the shafts operatively, a bridge mounted removably on the arm at the outer end thereof, and a pressure member under the control of an operator member and adjustable in the bridge in a direction

substantially parallel to the axes of rotation of the shafts.

In testimony that I claim the foregoing as my own, I have hereto affixed my signature in the presence of two witnesses.

LEO G. McMULLEN.
